(54) **WATER WHEEL**

(76) Inventor: **Charles Kenzie**

Charles Thoenig
Letters Patent

The schedule referred to in these Letters Patent and making part of the same containing a description in the words of the said to —
Thoenig himself of his "Improvement in the mode of applying
water to central discharging Pneumatic water wheels"

I call to witness these presents shall come. Be it known that I Charles Thoenig of the City of Troy in the County of Rensselaer and State of New York have invented a new and useful improvement in the mode of applying water to central discharging pneumatic water wheels and that the following is a full and exact description of the construction and operation of the said improvement as invented by me. Although there are several ways in which the pneumatic pipe of my improvement may be applied I shall describe that which I deem best. I construct a cast iron or wooden horizontal tank with strength proportioned to the head of water for which it is intended. The depth of said tank inside, the same as the length of the water wheel bucket (float). Inside in the center double the diameter of the wheel and all proportioned to the supply of water or the quantity of power required. Said tank (may if required) be left open at both ends and provided with flues and some other convenient pipe to receive by means of some办法 (otherwise) to the floor, (a float) through which the water is received. A circular opening is formed in the top and bottom of said tank for the admission of the wheel, which is of ordinary construction with a float and consisting of two rings with rectangular flats between said rings and some extending from the shaft to the center of the float close to the edge of said opening in the tank both at top and bottom. Holes are made of suitable size in the castings or plates at equal distances apart for the purpose of receiving the points of the gates hereinafter mentioned. Also the same number

of equidistant holes are made on this side of these at the top, opposite the outer end of the gates which are to receive the points of the long bar, which the gates are of course attached. The gates may be six, eight, or ten in number according to the size of the wheel and are segments of circles of about the same radius as the periphery of the wheel and may be constructed of wood, cast a wrought iron or a broad bar equal to the depth of the tank, having, on its side the inner ends, sufficiently strong, to resist the pressure of water which are inserted in the holes near the circular openings in the tank above mentioned and acting, as being. The outer end of each gate when closed extends a short distance past the inner end of the preceding gate and when open they form a series of small passages or inlets to the wheel through which the water acts at an angle of about forty-five degrees on the bucket or float of the wheel itself and afterwards discharges toward the outer bath above and below the arms of the wheel. To open and shut these gates a series of angular pointed levers each consisting of a short arm attached to a post with a sliding pivot that passes through the outer series of holes above mentioned in the top of the tank and receives a screw nut on the upper side of the tank to secure it to its place and also another screw nut to be concealed at its bottom, and in the upper end of the outer end of the gates by links constituting an angular joint as to allow the operation of wheel to close or open the gates by simply turning the points and these points being connected to a suitable wheel or wheel or other suitable machinery, a simultaneous closing or opening of all the gates to any desired degree is effected by simply turning said wheel by which means the quantity of water applied to the wheel admits of great regulation and its maximum effect being secured in any stage of water as the head may always be kept full. Now to have a claim of my own invention and not previously secured in the above described water wheel and its apparatus, are the moveable gates or water guides and their respective connections with or in application to all water wheel machinery.

inventor's hand. In testimony that the foregoing, is a true specification of my said invention I have hereunto set my hand
the eleventh day of June A.D. 1886.
